DESIGN FOR AN ELECTRICAL REACTOR

Walter J. Garlick, Jr., Glen Ridge, N. J., assignor
to American Transformer Company, Newark,
N. J.

Application August 13, 1938, Serial No. 79,324

Term of patent 7 years

To all whom it may concern:

Be it known that I, Walter J. Garlick, Jr., a citizen of the United States, residing at Glen Ridge, in the county of Essex, State of New Jersey, have invented a new, original, and ornamental Design for an Electrical Reactor, of which the following is a specification, reference being had to the accompanying drawing forming a part thereof.

Figure 1 is a view looking down on the top of an electrical reactor showing my new design.

Figure 2 is a view looking upwardly at the bottom of the reactor.

Figure 3 is an end elevation of the terminal end of the reactor.

Figure 4 is a side elevation of Figure 3, looking from right to left.

I claim:

The ornamental design for an electrical reactor, as shown.
